UNITED STATES PATENT OFFICE.

GILBERT L. CROWELL, JR., OF ARLINGTON, NEW JERSEY, ASSIGNOR TO DOMINICK & HUFF, OF NEW YORK, N. Y., A JOINT-STOCK COMPANY, OF NEW YORK, N. Y.

DESIGN FOR A DISH, PLATE, OR SIMILAR ARTICLE.

61,222.

Specification for Design.

Patented July 18, 1922.

Application filed October 22, 1921. Serial No. 509,744. Term of patent 7 years.

To all whom it may concern:

Be it known that I, GILBERT L. CROWELL, Jr., a citizen of the United States, and a resident of Arlington, in the county of Hudson and State of New Jersey, have invented a new, original, and ornamental Design for a Dish, Plate, or Similar Article, of which the following is a specification, reference being had to the accompanying drawing, forming a part thereof.

The figure is a plan view of my border

shown applied to a round dish, the dotted line indicating that the border extends around the plate.

I claim:

The ornamental design for a dish, plate, or similar article, as shown.

GILBERT L. CROWELL, JR.
